RADIO ELECTROCARDIOGRAPH RECEIVER

Stanley S. Wulc, Lafayette Hill, Pa., assignor to Vector
Manufacturing Company, Incorporated, a corporation
of Pennsylvania

Filed July 20, 1961, Ser. No. 65,994

Term of patent 14 years

(Cl. D83—1)

FIG. 1 is a perspective view of a radio electrocardiograph receiver showing my new design with the cover in closed position.

FIG. 2 is a side elevation thereof as shown in FIG. 1.

FIG. 3 is a perspective view thereof with the cover open and the antenna in extended position, and

FIG. 4 is a reduced elevation thereof as seen from the left of FIG. 2.

I claim:

The ornamental design for a radio electrocardiograph receiver, as shown.
